(57) **CLAIM**

The ornamental design for a cleaning cart, as shown and described.

DESCRIPTION

The nature of this product is as a portable carrier for a dispenser of liquids primarily used for cleaning and sanitizing solutions.

FIG. 1 is a left, front, perspective view of a cleaning cart embodying our new design;

FIG. 2 is a front elevational view thereof;

FIG. 3 is a left side elevational view thereof;

FIG. 4 is a right side elevational view thereof;

FIG. 5 is a rear elevational view thereof; and,

FIG. 6 is a top plan view thereof.
